(57) **CLAIM**

The ornamental design for a lamp, as shown and described.

DESCRIPTION

FIG. 1 is a top plan view of a lamp, showing my new design;
FIG. 2 is a perspective view thereof;
FIG. 3 is a left side elevation view thereof;
FIG. 4 is a bottom plan view thereof;
FIG. 5 is a front elevation view thereof;
FIG. 6 is a right side elevation view thereof; and,
FIG. 7 is a rear elevation view thereof.
The broken lines in the drawings illustrate portions of the lamp which forms no part of the claimed design.
